UNITED STATES PATENT OFFICE.

EDWARD GURNEY, OF TORONTO, ONTARIO, CANADA.

DESIGN FOR A HOT-WATER OR STEAM RADIATOR.

SPECIFICATION forming part of Design No. 19,625, dated January 28, 1890.

Application filed September 5, 1889. Serial No. 323,091. Term of patent 7 years.

To all whom it may concern:

Be it known that I, EDWARD GURNEY, a subject of the Queen of Great Britain, residing at the city of Toronto, in the county of York, in the Province of Ontario, Canada, have invented and produced a new and original Design for Hot-Water or Steam Radiators, of which the following is a specification, reference being had to the accompanying drawings, forming part thereof.

Figure 1 is a perspective view of my newly-designed radiator. Fig. 2 is a sectional plan of one of the loops, which latter view is necessary to show the shape of the loop.

The leading features of my design consist of a series of substantially diamond-shaped loops, each loop having four sides, each of said sides being concaved and ornamented by a raised fancy design, the distinctive feature of which consists of a scroll formed by three raised ribbons.

A represents the outer loops, which are oblong in shape, and in cross-section are each made with four concaved sides *a*, a narrow edge *b* being formed between each side.

B represents three raised ribbons arranged in a scroll shape on each loop, passing below and through the raised fancy design, as indicated. Each loop is provided with a pair of legs *C*, curved outwardly and ornamented by heavy scroll-work. An elbow *D* is gracefully formed integral with the end loop at its upper end.

A detachable cap *E*, with ornamental scalloped sides, is placed on the top of the radiator.

I claim—

1. In a design for a radiator, as herein shown and described, the shape of the loop, comprising a series of vertical chambers, the outer chambers each having four concaved sides, substantially as shown.
2. The design for a radiator herein shown and described.

Toronto, July 20, 1889.

EDWARD GURNEY.

In presence of—

CHARLES C. BALDWIN,
F. R. CAMERON.
